UNITED STATES PATENT OFFICE.

JAMES H. HEPBURN AND ALFRED PIETZOLD, OF LA GRANDE, OREGON.

EJECTOR.

Application filed June 20, 1924. Serial No. 721,326.

To all whom it may concern:

Be it known that we, JAMES H. HEPBURN and ALFRED PIETZOLD, citizens of the United States, residing at La Grande, in the county 5 of Union and State of Oregon, have invented new and useful Improvements in Ejectors, of which the following is a specification.

This invention relates to ejectors and has 10 for an object the provision of a device of this character which in addition to being simple, inexpensive and durable in construction, is susceptible of ready application and manipulation and is possessed of a wide 15 range of usefulness, particularly in a kitchen or laundry, for handling liquids.

With the above and other objects in view, the invention further includes the following 20 novel features and details of construction, to be hereinafter more fully described, illustrated in the accompanying drawings and pointed out in the appended claims.

In the drawings:—

Figure 1 is an elevation of the device 25 showing its position in use, a sink being shown in section while a tub or container is shown partly broken away.

Figure 2 is a longitudinal central sectional view of the device per se.

Figure 3 is a top plan view of the same.

Referring to the drawings in detail wherein like characters of reference denote corresponding parts, the reference character 10 indicates a tubular body, a portion of the 35 bore of which is reduced as at 11. At one end, the body is provided with means for removable attachment to a spigot 12 and for this purpose is internally threaded as shown at 13, while extending around this end of the body are projections 14 which provide 40 finger grips to aid in attaching and removing the device.

Extending longitudinally of the tubular body 10 is a relatively small tube 15 which 45 extends into and is spaced from the wall of the reduced bore 11. The tube 15 extends through the wall of the tubular body so as to provide a nipple 16 over which may be secured one end of a hose 17. The opposite 50 end of this hose is adapted to extend into a tub or container 18.

The lower end of the body 10 is closed as 55 shown at 19 and located adjacent this closed end is a discharge opening 20 so that liquid passing through the tubular body 10 will

pass outward through the sides of the said body instead of the end. Mounted upon the body 10 and having a sliding fit thereon is a sleeve 21 which is preferably formed of rubber or other suitable material and which 60 has extending therefrom an outwardly flared apron 22, the latter extending from the discharge opening 20 as shown in Figure 2 of the drawings and providing an anti-splash device, whereby liquid passing 65 through the opening 20 will be deflected downward into the sink 23. In addition, the member which is formed by the sleeve 21 and the apron 22 may be moved to position the sleeve over the opening 20 so as to close 70 the said opening and prevent the escape of liquid therethrough, so that a combined anti-splash device and valve is provided. The amount of liquid passing through the opening 20 may be regulated by the position 75 of the sleeve 21.

While the device is shown as applied to a spigot, other means may be provided for setting up an ejecting action in the device, although the said device is primarily in- 80 tended to be used with a spigot.

In the use of the invention, the sleeve 21 may be positioned over the opening 20 so as to close the latter and when the spigot is opened, water will flow through the hose 17 85 into the tub 18. When it is desired to empty the tub, the spigot is opened to permit water from the spigot to pass through the tubular body 10 to effect the removal of water from the tub 18. Should the tub 18 be 90 sufficiently elevated it will be only necessary to open the spigot to effect an initial flow through the hose 17, after which the spigot may be closed and the siphonic action will continue until the tub is empty.

The invention is capable of various other uses. For example, when the device is attached to a faucet, the receiving end of the hose may be used for skimming various substances, while the latter are cooking, it being only necessary to turn on the faucet and to manipulate the receiving end of the hose over the surface of the liquid being skimmed.

The invention is susceptible of various 105 changes in its form, proportions and minor details of construction and the right is herein reserved to make such changes as properly fall within the scope of the appended claims.

Having described the invention what is claimed is:—

1. An ejecting device comprising a tubular body adapted at one end to be connected to a source of fluid supply, a combined cut off valve and anti-splash member at the opposite end of the body and a tubular member carried by said body and having a portion disposed in the body and spaced from the wall thereof and directed toward the cut-off valve and spaced from the latter. 35
2. An ejecting device comprising a tubular body adapted at one end to be connected to a source of fluid supply, the opposite end of said body being closed and provided with a discharge opening adjacent the closed end, an annular member slidable upon the body near the closed end and providing a combined anti-splash member and cut-off valve 40 and a tubular member extending into the body and spaced from the wall thereof. 45
3. An ejecting device comprising a tubular member adapted at one end to be connected to a source of fluid supply, the opposite end of said body being closed and provided with a discharge opening adjacent the closed end, a sleeve having a sliding fit upon the body and adapted to close the discharge opening, an outwardly flared apron extending from the sleeve and defining an anti-splash element and a tubular member carried by said body and having a portion 50
4. An ejecting device comprising a tubular body adapted at one end to be connected to a source of fluid supply, a cut-off valve at the opposite end of the tubular member and a tubular member carried by said body and having a portion disposed in the body and spaced from the wall thereof and directed toward said cut-off valve and spaced from the latter, the said tubular body having a forward bore portion of reduced diameter and the said portion of the tubular member being spaced from said reduced bore portion. 55
5. An ejecting device comprising a tubular body adapted at one end to be connected to a source of fluid supply, a cut-off valve at the opposite end of the tubular body and a tubular member having a portion arranged within the tubular body and directed toward and spaced from the cut-off valve and also having an arm extending laterally to 60 and exteriorly of the body, the said tubular body and the said tubular member being formed in one piece of material and the forward portion of the bore of the tubular body being of reduced diameter. 60

In testimony whereof we affix our signatures.

JAMES H. HEPBURN.
ALFRED PIETZOLD.
